UNITED STATES PATENT OFFICE.

JAMES B. WILLIAMS AND JOSEPH P. SMITH, OF GLASTONBURY, CONN.

THILL-COUPING.

SPECIFICATION forming part of Letters Patent No. 351,083, dated October 19, 1886.

Application filed April 6, 1885. Serial No. 161,281. (No model.)

To all whom it may concern:

Be it known that we, JAMES B. WILLIAMS and JOSEPH P. SMITH, both of Glastonbury, in the county of Hartford and State of Connecticut, have invented a certain new and useful Improvement in Shackle-Joints, of which the following is a description, reference being had to the accompanying drawings, where—

Figure 1 is a side view of one form of a carriage-shackle embodying our invention. Fig. 2 is a bottom view of the same. Fig. 3 is a view in cross-section of the same on plane denoted by line $\alpha\alpha$ of Fig. 1. Fig. 4 is a detail view of several forms of renewable bearings. Fig. 5 is a plan view of an alternate form of a carriage-shackle embodying our improvement. Fig. 6 is a detail view in section through the bolt and shackle on plane denoted by line yy of Fig. 5. Fig. 7 is a front view of a whiffle-tree-shackle. Fig. 8 is a view in vertical cross-section through the pivot of the device on plane denoted by line $x'x'$ of Fig. 7. Fig. 9 is a sectional view of the parts similar to those shown in Fig. 8, except that the removable bearing e has a larger opening through it.

Our improvement relates more particularly to the class known as "carriage-shackles;" and it consists in the combination, with a shackle, of a removable bearing of peculiar configuration, so combined and arranged in the device as more effectually to permit of the taking up of either endwise or lateral wear of the bearing parts by simply tightening up the bolt connecting the several parts, as more particularly hereinafter described.

A minor feature of the invention consists in the provision in such removable bearing of a hole of larger diameter than the securing-bolt passing therethrough—that is, when that kind of a securing device is employed.

In the accompanying drawings, the letter a denotes a carriage-shackle as a whole; b , the inner end or shank of a thill having an eye, c , through which the bolt d passes to unite the coupling and thill.

In the form of thill-coupling shown in Figs. 1 to 3 the body of the shackle is made in two pieces, a' a'' , bearing upturned ears a^3 a^4 , respectively, which are perforated sidewise for the passage of the bolt d . The inner faces of these ears upon each side of the bolt-hole and

one or both faces of the shank b of the thill are provided with curved or equivalent recesses, and in these recesses and between the ears on the coupling and the shank of the thill are seated removable bearings e , which conform in outline to the outline of the socket, and which are also perforated for the passage of the bolt d . These bearings e may be of metal—as iron, steel, or Babbitt metal, or of an elastic material, as india-rubber or leather—but are preferably of a very firm compact material, and in shape these bearings are cylindrical, or, preferably, spherical, spheroidal, oval, or similar shaped body having a rounded surface. In each shape, however, the hole through the bearing and that through the thill-shank for the passage of the bolt are preferably larger in diameter than the bolt, so that when the parts are all put together, as shown in Fig. 1, the shearing strain in using the device does not come upon the bolt, but on the bearings that are interposed between the ear on the body of the coupling and the shank of the thill or like part.

Instead of the form above described, in which the shank of the thill is held between the two ears on the coupling, the shank b and coupling a may be halved together, as shown in Figs. 5 and 6, and in this form the renewable bearing e is placed between the adjacent surfaces in a similar position as in the other form.

In Figs. 7 and 8 our improvement is shown as embodied in a shackle adapted to connect the cross-bar of the shafts or pole of a wagon and a whiffle-tree, and in this the bearing is located between parts precisely as in the devices already described. Whenever the parts wear so as to become loose and rattle, they may be tightened by screwing up the nut on the bolt that joins them; but our device is less liable to become loose than prior devices, and has the further advantages of being easily and cheaply repaired by replacing a worn out bearing-piece. These bearing-pieces may, if desired, fit so loosely about the bolt or pin as to more nearly resemble a washer or narrow ring, the outer edge of the ring, however, forming the bearing surface for the two parts of the shackle, as in the forms already described.

It is understood that a clamp or like means of holding the shackle parts together may be used in place of the bolt *d*.

We are aware that removable bearing pieces 5 of cylindrical and double conoidal form have been employed; but the angular edges in such constructions render them objectionable, because of the shearing action they have on the parts with which they are in contact.

10 We claim as our invention—

1. In combination, a shackle-body, *a*, having ears *a³* *a⁴*, having curved recessed inner faces, thill-shank *b*, with eye *c*, having curved recessed sides, removable bearing-pieces *e*, having faces curved to correspond with the recessed faces located between said recessed faces of the shank and ears, and bolt *d*, all substantially as described.

15 2. In combination, a shackle body, a thill-

shank, a removable spherical or spheroidal 20 bearing seated in a corresponding recess formed in the adjacent faces of both shackle-body and shank of the thill, and means, substantially as described, for holding the parts together, as set forth.

25 3. In combination with the shackle parts having curved recessed bearing faces, a removable perforated bearing piece corresponding to and fitted in such recesses, and a bolt 30 of smaller diameter than the hole in the bearing-piece passing therethrough and securing the shackle parts together, as and for the purpose set forth.

JAMES B. WILLIAMS.
JOSEPH P. SMITH.
